CLOTHES CARRIER WITH REMOVABLE BAG

William G. Persinger, Burbank, Calif.

Application November 19, 1948, Serial No. 60,949

4 Claims. (Cl. 248—101)

1

This application has relation to a clothes carrier and has particular reference to a device of this type which is equipped with a detachable clothes bag.

It is the object of the invention to provide a collapsible carrier frame including elements for receiving a clothes bag and for locking the bag firmly in position on the carrier. It is a further object of the invention to provide a clothes bag which is so shaped that it may be applied directly to said carrier elements for attachment to the carrier, thereby to eliminate the buttons, snap fasteners and other similar devices employed in such clothes bags of this type that have come to my notice.

The invention will be better understood from the following detail description and reference is invited to the accompanying drawings in which a preferred form of the invention is illustrated.

In the drawings:

Fig. 1 is a side elevational view of a clothes carrier having a clothes bag mounted in position thereon as in practice;

Fig. 2 is a substantially corresponding end view of the device;

Fig. 3 is a fragmentary view on a larger scale of the upper portion of one of the carrier members illustrated in Fig. 2;

Fig. 4 is an end view of the upper portion of the carrier illustrating the initial step in mounting the bag in position thereon;

Fig. 5 is a substantially corresponding plan view of the carrier; and

Fig. 6 is a fragmentary view illustrating the second step necessary in order to mount the bag in position on the carrier.

As indicated in Figs. 1 and 2, the carrier frame consists of two members 1, 2 which are pivotally assembled, as indicated at 3. These members are made from strips of material which are made U-shaped in cross-section in order that the outer surfaces thereof may present a smooth curved outline which is pleasant to handle. As best shown in Figs. 3 and 4, a bag securing element, in the form of a resilient wire 5, is mounted within the outwardly curved material of one leg of the carrier frame member 1, near the top thereof, and it is noticed that this element extends the entire distance across the frame member, within the curvature of the horizontally disposed top portion thereof. A portion of the leg of the carrier frame has been indented, as indicated at 6, in order to provide a socket of a size to seat therein the lower end of the element 5 and a second indentation 7 is made in the leg below the

2

socket 6 to form a stop against which the end of the element 5 comes to rest when the element is placed in position within the carrier frame member. When so mounted, it is found that the resilience of element 5 maintains the upper horizontal portion thereof pressed against the inner surface of the frame member and it is important to note that the free end 9 of the element is downwardly curved to ride within the curvature of the frame. It is to be understood that there is one bag securing element within each frame member.

As above stated, the bag 15 is mountable on the resilient element 5 without having to resort to the use of buttons or other fasteners. The bag has rectangular sides and it is made along the upper edges thereof, at the ends of the bag, with seams 16, 17 of a size freely to admit the ends of the fastening elements 5. For the purpose of mounting the bag in position, it is first required to draw the ends of the fastening elements out from under the inner surface of the frame member, substantially as indicated in Fig. 4, against the tension of the fastening element, 15 whereupon the bag is raised into the position indicated at Fig. 4 to cause the end of the fastening element to pass through the seam 16 of the bag. The element is then snapped back in position within the carrier frame to clamp the end of the bag securely in position thereon.

In order to mount the opposite end of the bag in position on the element 5a of the other frame member, it becomes necessary partly to collapse the carrier frame and to swing the bag above the frame, substantially into the position indicated in Fig. 6. It is then a simple matter to slip the seam 17 of the bag on to the element 5a and to snap this element back into position within the frame member. It is then merely required to push the bag down into the position shown in Fig. 1 and to spread the frame members apart, whereupon the device is ready for use, the bag being held firmly in position within the frame members by the tension of the resilient fastening elements. Withdrawal of the free end 9 of the fastening element may be facilitated, as indicated in Fig. 3, by so shaping the end 9 that sufficient space 11 is present above the element for insertion of the fingers.

It is important to note that, when the bag is mounted in position on the frame as above described, the material of the bag covers the entire upper surfaces of the frame members and that no fastening elements of any sort are present to project from this smooth and soft operating

3

surface of the carrier. It is furthermore important to note that when the bag is detached from the carrier frame, it may be laundered and ironed without interference by fasteners and folded smoothly together for storing purposes when not in use. The carrier may be fitted with wheels 12 at the end of one or both frame members, if desired, and the inner frame member 1 may be fitted with cross braces 13, as indicated in Fig. 2.

I claim:

1. A carrier for a clothes bag having seams along two opposed edges thereof, said carrier including two frames made from thin strips of material substantially semi-circular in cross-section, each frame including a horizontal cross-bar 15 and a leg dependent from each end thereof, a horizontally disposed rod extending through said frames intermediate their ends to form a pivotal point for the carrier, the material of each frame near the top of one leg thereof being inwardly extruded to form a socket and a stop below the socket, and a resilient clamping rod seated in each of said sockets against said stops, the upper portion of each of said rods being flexed to rest against and exert pressure against the inner bottom surface of the cross-bar of each frame, each clamping rod being manually movable to swing the free end thereof clear of the bar for insertion into one of the seams of the bag, by its resilience to return to its initial position firmly to clamp the bag seam against the inner surface of the bar.

2. A carrier for a clothes bag comprising, a collapsible stand consisting of two frames, each frame being made from strips of thin material substantially semi-circular in cross section and bent to provide at the top thereof, a horizontally disposed cross-bar and legs downwardly extending therefrom, the convex surface of the frame material being outwardly directed thereby to provide an inwardly directed groove therein, a transverse rod pivotally interconnecting the legs of the frames intermediate their ends, and a resilient L-shaped bag clamping element for each frame, said element being seated within the groove of said frame and having upwardly and inwardly extending portions said inwardly extending portions resting against the inner surface extending upwardly and inwardly to rest against the inner surface of the horizontally disposed frame cross-bar, the lower end of the element being secured in position within the groove of the frame leg, one element adapted to be swung out of the cross-bar and inserted into one of the seams of the bag and swung back, whereupon the bag is swung over both cross-bars of the frames and the element of the other frame inserted in the opposite seam of the bag.

3. A carrier for a clothes bag comprising, a collapsible stand consisting of two frames, each frame being made from strips of thin material substantially semi-circular in cross section and bent to provide at the top thereof a horizontally

disposed cross-bar and legs downwardly extending therefrom, the convex surface of the frame material being outwardly directed thereby to provide an inwardly directed groove therein, a transverse rod pivotally interconnecting the legs of the frames intermediate their ends, and a resilient L-shaped bag clamping element for each frame, said element being seated within the groove of said frame and having upwardly and inwardly extending portions said inwardly extending portions resting against the inner surface extending upwardly and inwardly to rest against the inner surface of the horizontally disposed frame cross-bar, the lower end of the element being rotatably secured in position within the groove of the frame leg.

4. A carrier for a clothes bag having seams along two opposed top edges thereof, said carrier comprising, a collapsible stand consisting of two frames, each frame being made from strips of thin material substantially semi-circular in cross section and bent to provide at the top thereof a horizontally disposed cross-bar and legs downwardly extending therefrom, the convex surface of the frame material being outwardly directed thereby to provide an inwardly directed groove therein, a transverse rod pivotally interconnecting the legs of the frames intermediate their ends, and a resilient L-shaped bag clamping element for each frame, said element being seated within the groove of said frame and having upwardly and inwardly extending portions said inwardly extending portions resting against the inner surface extending upwardly and inwardly to rest against the inner surface of the horizontally disposed frame cross-bar, the lower end of the element being secured in position within the groove of the frame leg, one element adapted to be swung out of the cross-bar and inserted into one of the seams of the bag and swung back, whereupon the bag is swung over both cross-bars of the frames and the element of the other frame inserted in the opposite seam of the bag.
